E. J. McCauley.
EDGE FINISHER FOR COLLARS AND CUFFS.
APPLICATION FILED APR. 24, 1908.

927,670.

Patented July 13, 1909.

UNITED STATES PATENT OFFICE.

EDWARD JOSEPH McCUALEY, OF VALLEJO, CALIFORNIA.

EDGE-FINISHER FOR COLLARS AND CUFFS.

No. 927,670.

Specification of Letters Patent.

Patented July 13, 1909.

Application filed April 24, 1908. Serial No. 428,996.

To all whom it may concern:

Be it known that I, EDWARD J. McCUALEY, a citizen of the United States, residing at Vallejo, in the county of Solano and State of California, have invented certain new and useful Improvements in Edge-Finishers for Collars and Cuffs; and I do declare the following to be a full, clear, and exact description of the invention, such as will enable others skilled in the art to which it appertains to make and use the same.

This invention relates to improvements in edge finishers for collars and cuffs.

The object of the invention is to provide a device of this character formed in separate sections, one of which is under spring pressure whereby the same is yieldingly held in engagement with the edge of a collar or cuff when applied between said sections and whereby an improved finish is imparted to the edge of the collar or cuff.

With this and other objects in view, the invention consists of certain novel features of construction, combination and arrangement of parts as will be described and particularly pointed out in the appended claims.

In the accompanying drawing, Figure 1 is a side view of a hand edge finisher showing the application of my improvements thereto; Fig. 2 is a vertical sectional view; Fig. 3 is a top plan view of the same.

Referring to Figs. 1, 2 and 3 of the drawings, 1 denotes a hand edger or finisher, which consists of a suitable base, 2, on which is arranged a tubular standard, 3. On the upper end of the standard, 3, is arranged a hollow head, 4, which is substantially rectangular in shape, one side of which is curved or arc-shaped, as shown. On the upper side 40 of the head, 4, adjacent to its opposite square corners are formed upwardly projecting apertured bearing lugs, 5, between which is pivotally mounted an upper finishing plate, 6, on the curved or front edge of which is formed a depending segmental flange, 7, which is adapted to engage or fit into a segmental recess, 8, formed in the adjacent upper edge of the curved side of the head, 4, as shown.

Screwed in or otherwise secured to the upper side of the hollow head 4 is a centrally disposed upwardly projecting rod, 9, which projects through a centrally disposed passage, 10, formed in the plate, 6. The passage 10 is of greater diameter than the rod, 9, to permit a limited upward swinging movement of the plate, 6. On the rod 9 and bear-

ing on the plate, 6, over the passage 10 is a washer plate, 12. The upper end of the rod, 9, is threaded and on said threaded end is arranged an adjusting nut, 13, between which and the washer, 12, is arranged a coiled spring, 14, the tension of which is regulated by means of the adjusting nut, 13. The pressure of the spring, 14, is exerted to yieldingly hold the plate, 6, down on the upper side of the head, 4, and the flange 7 thereon in position to engage a collar placed in the recess, 8, in the front side of the head.

The hollow head, 4, may be heated in any suitable manner, but is here shown and is preferably adapted to be heated by steam which is introduced thereto through an inlet or feed pipe, 15, which enters the lower end of the standard and extends upwardly therethrough to near the upper end of the standard adjacent to its connection with the hollow head. In the standard, 3, around the feed pipe, 15, is formed an exhaust passage, 16, into which the steam enters after being injected into the head from the end of the feed pipe. The exhaust steam is discharged from the standard near its lower end through an exhaust pipe, 17, which is connected to a suitable discharge port in the standard.

In operation the edge of the collar or cuff after being slightly dampened is inserted and drawn between the lower edge of the flange 7 of the finishing plate and the adjacent wall of the recess, 8, in the heated head. The spring 14 which bears against the finishing plate will force the flange 7 down upon the collar which rests in the segmental recess 8. The sides of the collar will therefore be finished by the floor of the recess and the underneath edge of the flange 7, while the edge of the collar will be finished by engaging the vertical wall of the recess.

By providing an edge finisher such as shown and described, edges or folds of different thicknesses may be readily accommodated and finished between the yieldingly engaged parts of the device, thereby dispensing with the necessity of providing a plurality of grooves of different widths to accommodate different thicknesses of material.

From the foregoing description, taken in connection with the accompanying drawing, the construction and operation of the invention will be readily understood without requiring a more extended explanation.

Various changes in the form, proportion and the minor details of construction may

be resorted to without departing from the principle or sacrificing any of the advantages of the invention as defined in the appended claims.

5 Having thus described my invention, what I claim as new and desire to secure by Letters-Patent, is:

1. In an edge finishing machine for collars and cuffs, a hollow stationary head having 10 on one side a collar receiving recess, provided with a horizontal wall and a vertical edge finishing wall, a finishing plate hingedly mounted on said base and provided with an aperture, a flange formed on said plate to 15 enter the recess in said head, said flange having a horizontal wall adapted to co-act with the horizontal wall in said recess to smooth and finish the sides of the collar near its edge, a standard secured to the head and projecting 20 through the aperture in the plate, a spring surrounding said standard to yieldingly hold the horizontal wall of said flange in engagement with the collar, means to adjust the spring, and means whereby said head is 25 heated.

2. In an edge finishing machine, for collars and cuffs, a hollow stationary head hav-

ing in one side a segmental collar receiving recess provided with a horizontal wall and a vertical edge finishing wall, a finishing plate hingedly mounted on said head and provided with an aperture, a flange formed on said plate, to enter the recess in said head, said flange having a horizontal wall, adapted to coact with the horizontal wall in said recess to smooth and finish the sides of a collar near its edge, a standard secured to the head, and projecting through the aperture in the plate, a spring surrounding the standard for pressing the plate in engagement with the head, means to adjust said spring, a tubular supporting standard communicating with said hollow head and forming an exhaust passage therefrom, a steam inlet pipe in said standard whereby steam is conducted to said head to heat the same, and a steam exhaust pipe connected to said standard.

In testimony whereof I have hereunto set my hand in presence of two subscribing witnesses.

EDWARD JOSEPH McCaULEY.
